UNITED STATES PATENT OFFICE

2,610,353

DETACHABLE DRAWER STOP

Joseph F. Hufnagel, Los Angeles, Calif.

Application July 22, 1949, Serial No. 106,158

1 Claim. (Cl. 16—82)

1

This invention relates to detachable drawer stops, to be placed on the rear wall of a drawer for the purpose of stopping the outward movement of a drawer when it has reached its limit, and to prevent its being pulled clear of its slide-way and dropping on the floor.

The principal object of the invention is to provide a stop with spaced legs or extension, which can be placed on the rear wall of a drawer and which will function as a stop when the drawer has been pulled out to the limit.

Other objects of the invention are: to provide a stop of the character referred to having two legs or extensions to straddle on the rear wall of a drawer and which also has an upper part projecting above the wall on which it is mounted and which is rigid and of such form as to constitute a strong stop element, not subject to bending or breaking; to provide a stop of the character referred to in which the legs or extensions which straddle the rear wall of a drawer are heavier than the upper part, whereby to cause said stop to stand upright on said drawer and when tilted to return to upright position when released.

In order to explain my invention, I have shown one practical from thereof on the accompanying sheet of drawings, in which:

Figure 1 is an end view of a desk, with a part broken out, to show the drawer with one of the stops, constituting the invention, in place thereon;

Figure 2 is a side elevation of the invention;

Figure 3 is a sectional view of the invention, indicating its position on a wall, indicated in light broken lines, and showing a struck-in lip on which said stop rests on the edge of a wall;

Figure 4 is an open side view of the invention;

Figure 5 is an end view, looking down into the device; and

Figure 6 indicates how the stop can be laid down on the edge of a wall and will swing into upright position when released.

Referring to the drawings in detail, a desk 7 is shown in Fig. 1, with a drawer 8, pulled partially out, with the rear wall 9 partly in section, and showing the invention on said wall. The slide-way for the drawer is designated 10, and the front desk, or frame wall against which said stop will strike, is designated 11.

The invention as a whole is designated 12, and in the present showing is of channel form, with the side walls 13, 13, and the rear wall 14, with a struck-in lip 15, between the side walls 13, 13, as seen in Figs. 3, 4 and 5. The side walls 13, 13, are extended in length and constitute spaced legs to straddle over the back wall 9 of the drawer. Said legs or extensions 13', 13' are sufficiently long to be heavier than the top part of said device so they will swing downwardly into upright position when placed on the wall. The struck-in lip or member 15 forms a flat rest or support for the device on the wall, as indicated, so that the device will remain in place on the wall, and in upright position at all times. If desired, said device can be further secured in place by screws through the holes 16 in the ends of said legs.

The form of the invention can be changed, as to its cross sectional form, if desired, but the present embodiment is economical to make, is rigid and sufficiently strong to withstand the stop engagement with the front of the desk at 11.

I do not, therefore, limit the invention to the showing made, except as I may be limited by the hereto appended claim.

I claim:

A drawer stop as shown consisting of a channel-like member having side walls and a rear wall connecting said side walls, said side and rear walls providing an upper portion which is substantially square in cross section, the side walls being extended to form two spaced legs to straddle a drawer wall, and said rear wall having its lower end struck in to form a horizontal lip between said side walls to rest upon the top edge of said drawer wall, said two spaced legs being heavier than the upper portion to swing by gravity to vertical position with the upper ends of said side walls and said rear wall constituting the stop on said drawer.

JOSEPH F. HUFNAGEL.
